SPLINT

Jacob Clem Butler, Milford, Del.

Application January 21, 1943, Serial No. 473,122

11 Claims. (Cl. 128—87)

The present invention relates to splints, and more particularly to a two-piece external splint for use in the treatment of a broken, dislocated, or fractured mandible.

The principal object of the invention is to provide a practical splint adapted for universal use in the treatment of mandibular injuries and which splint is capable of use for such treatment irrespective of the size and/or shape of the mandible and which can be adjusted to apply various types of stress, as required.

Another object of the invention is to provide an external mandibular splint that can be used in combination with interdental types of splints, particularly where it is desired to maintain immobility of the mandible.

Another object of the invention is to provide an external mandibular splint adapted for use in either edentulous or dentulous types of fractures.

Still another object of the invention is to provide an external mandibular splint that may be quickly applied and adjusted for either emergency use until the patient is hospitalized, or for permanent use.

Still another object of the invention is to provide a mandibular splint that may be easily and quickly removed, if necessary, even by the patient himself in case of nausea, thereby avoiding possible strangulation.

A further object of the invention is to provide an adjustable external mandibular splint contoured to fit the curve of the lower jaw and thus support the mandible during the bone-knitting stage.

Still a further object of the invention is to provide a mandibular splint which will permit X-rays to be taken of the mandible while the splint is held in place.

A still further object of the invention is to provide a mandibular splint made of plastic, hard rubber, etc., that may be readily cut or filed away to permit access for surface treatment, particularly in cases where the fracture of the mandible is due to a gunshot wound or shell fragment.

A still further object of the invention is to provide an external mandibular splint that may be attached to the head by means of straps or buckles, or by means of ordinary bandage.

Other and further objects of the invention will be apparent from the following description, taken in conjunction with the accompanying drawings, in which:

Figure 1 illustrates the two section mandibular splint of the present invention held in place on a patient's face by attaching means comprising

suitable straps and buckles cooperating with said splint to apply vertical stress;

Figure 2 is a view similar to Figure 1 but showing the splint and attaching means as they appear in a full-face view;

Figure 3 is an enlarged sectional view through one of the splint sections, taken on the line 3—3 of Figure 1, and particularly illustrating one manner in which the loops or fastening members may be embedded in the splint material;

Figure 4 is an enlarged sectional view through one of the splint sections, taken on the line 4—4 of Figure 1;

Figure 5 is a view of the splint sections as viewed from the side thereof which engages the chin and lower jaw; and

Figure 6 illustrates the manner in which the splint sections may be attached by ordinary bandage material to apply protrusive stress.

Referring now to the drawings, the splint is generally indicated by the numeral 1, and comprises two sections 2 and 2a which normally are identical in shape and configuration, except that one is generally contoured to fit the right side of the chin and jaw and the other is contoured to fit the left side. As will be apparent from Figures 1 and 2, each of the splint sections 2 and 2a includes a chin-engaging portion 3 at its forward end adapted to be positioned in engagement with the frontal portion of the chin, and a temple portion 4 at its rear end and including a part 4a extending upwardly to a point adjacent the ears (not shown). Each of the splint sections also includes a lower inwardly curved portion 5 extending rearwardly from the chin-engaging portion 3 toward the temple portion 4 and adapted to engage the underside of the jaw.

The distance between the chin-engaging portions 3 of the splint sections 2 and 2a is adapted to be varied to suit the width of the chin and lower jaw angle of various patients. Thus, a fastening member 6 is preferably embedded in each of the splint sections 2 and 2a at a point a short distance inwardly from the edge of the chin-engaging portions 3, the fastening members being substantially staple-shaped and providing external loops adapted to be used in connecting the sections 2 and 2a together. A second fastening member 7 is mounted in each of the sections 2 and 2a in the curved portion 5 intermediate the ends of said sections, the fastening members 7 being arranged to provide loops at an angle to the fastening members 6.

In applying the splint to a patient, the splint sections 2 and 2a can be readily positioned in

the proper spaced relation by inserting a strip of ordinary adhesive tape 8 under the fastening members or loops 6 and then overlapping the ends of said tape in front of the splint sections. This will enable the splint sections to be spaced apart or adjusted by said tape to accommodate any width of chin. Any necessary readjustment can be quickly made by loosening the end of the tape, taking up or providing slack, and then fastening said end in place again. In order to adjust the splint sections 2 and 2a for the proper angle in the distal area of the mandible, a second strip of adhesive tape 9 is passed through the fastening loops 7 and its ends then overlapped below the chin of the patient to adjust or secure the sections 2 and 2a in proper angular relation.

It will be clear from the foregoing that the invention provides a practical splint capable of substantially universal use in that by suitable adjustment of the tape 8, the splint sections 2 and 2a can be spaced to suit any width of chin and by suitable adjustment of the tape 9, said splint sections can be connected together on any angle to accommodate the angularity of the mandible in the distal area.

The fastening members 7, as has been previously noted, are positioned at an angle, so that when the splint is in use the adhesive tape 9 secured to said fastening members is positioned so that it has no tendency to choke or constrict the breathing of the patient. Any further adjustment of the tape 9 to change the angle of adjustment of the sections 1 and 2 can be made in the same manner described in connection with the tape 8.

The temple portions 4a of the sections 2 and 2a carry fastening loops or members 10, 11 and 12 which, for convenience, are arranged in stepped relation, as best illustrated in Figure 1. The loops 10, 11 and 12 are also horizontally or laterally spaced relative to each other to permit the application of retrusive, vertical, and protrusive stress, respectively, as will be pointed out more fully hereinafter. The manner of embedding the fastening members 10, 11 and 12 in the splint sections 2 and 2a is best shown in Figure 3, wherefrom it will be noted that the extremities of said fastening members carry an enlargement 13 which, upon being embedded, prevents said fastening members from being pulled out of the splint sections. It will be understood that the fastening members 6 and 7 are preferably similarly secured in the splint sections 2 and 2a.

It will be noted that, while the fastening members 10, 11 and 12 are arranged at different vertical heights relative to the respective temple portions 4a, they are also spaced horizontally enabling each to be used independently as a means for attaching the splint as a whole to the head. Figure 1 illustrates the manner in which the splint may be applied when it is desired to exert a vertical stress upon the mandible. In such instance, the middle fastening members 11 have the headgear attaching means secured thereto. A convenient means for attaching the splint is here illustrated as comprising a strap 14, which extends transversely of the head, and through the loops 11, the free ends 15 of said straps passing through suitable buckles 16, whereby a suitable stress can be applied to the mandible by adjusting the strap ends 15 upon the opposite sides of the head. The strap 14 is fastened by a rivet 17 or other suitable means to a second strap 18 which extends around the head and is provided with a suitable buckle 19, prefer-

ably positioned at the forehead. Obviously, the strap 18 will prevent displacement of the strap 14 and thereby enable the desired stress to be applied to the mandible through the splint sections 2 and 2a. The headgear comprising the straps 14 and 18, and the buckles 16 and 19 is of such character as to be removable by a patient in case of nausea, etc.

The strap 14 is also adapted to have the ends 10, 15 thereof extend through the loops 10 or 12, so that stress may be applied to the mandible through the splint to meet other conditions. For example, by passing the ends 15 through the loops 10 of each of the splint sections, a retrusive stress may be applied in the case of a protrusive dislocation or displacement. Similarly, the strap ends 15 may be passed through the loops 12 to apply protrusive stress to overcome the natural displacing tendencies of the throat and any muscles thereof which may have become spastic due to injury.

It will be apparent from the foregoing, that the present splint, by virtue of its two-piece construction, is adapted for universal use and 25 enables the necessary and proper stress to be applied for breaks, fractures or dislocations of the mandible. The use of adhesive strips 8 and 9 for chin and angular adjustment not only provides a sort of flexible hinge for the splint sections 2 and 2a, but also enables the splint sections to be adjusted with a minuteness of accuracy that could not be attained with leather straps or similar strap fastening means. Once 30 the strips of adhesive tape have been properly adjusted, there is no danger of slippage and the adjustment, therefore, remains permanent for the individual.

Figure 1 further illustrates the adaptability of the present splint for use in treating patients 40 having jaw wounds, cuts or infections that normally would be difficult to treat without disturbing the adjustment of the splint. Thus, in the case of a surface ailment requiring treatment in the region of the mandible, a portion 45 of the splint section 2 can be removed, as indicated at 20, to expose said ailment. In this manner, it is possible to render the necessary surface treatment without removing or changing the adjustment of the splint.

The splint comprising the present invention 50 may be made of any suitable material, such as light metal or hard rubber, but is preferably made of transparent plastic material, with the exception of the loop elements 6, 7, 10, 11 and 12 which, 55 for convenience, are preferably made of metal and embedded in the plastic. When the splint sections are made of non-metallic material they afford the advantage of permitting X-rays to be taken. However, it is to be understood that the 60 present invention is not to be limited or restricted to fabrication by any particular material or combination of materials, nor to the particular manner in which the loop elements are secured to the splint sections.

Figure 6 further illustrates the adaptability 65 of the invention for either emergency or permanent use, in that it shows one manner of securing the splint to the head by use of ordinary bandage. As is here shown, a stay bandage 25 70 is wrapped around the head and its free end secured by adhesive or any other means (not shown). A second strip of bandage 26 is threaded under the loops or fastening members 12 to apply a protrusive stress to the mandible. The 75 free ends of the strip of bandage 26 are tied to-

gether at the top of the head, and a strip of adhesive 21 is applied across the strip of bandage 26 adjacent the temples to prevent its displacement relative to the stay bandage 25. In this manner, the mandibular splint may be applied and attached to a patient without using the headgear comprising the straps and buckles shown in Figures 1 and 2.

Fig. 6 still further illustrates the adaptability of the present splint for use in applying stabilizing tension in cases of extreme displacement of the mandible due to spasm, frequently resulting from delay in treatment. In this connection, each of the splint sections 2 and 2a is provided with an additional loop or fastening member 33 positioned below and forwardly of the loop 10 at a point about midway of the length of the splint sections. As will be noted, the loop 33 is so arranged that a rubber band 34 may be passed therethrough and its ends 35 secured by a safety pin 36 to the bandage 25. The rubber band 34 will apply the auxiliary, constant upward tension necessary to maintain the mandible in place until the spasms subside.

Obviously, the loop 33 and a rubber band or any other suitable tension means may also be used to apply a stabilizing tension in the treatment of maxillary fractures when greater or supplemental pressure is required in the anterior region. The loop 33 is also adapted to be used to provide auxiliary pressure when a constant occluding pressure is essential to hold the fragments of the mandible in their correct normal anatomical position.

It will be manifest that the splint of the present invention is adapted for use in the treatment of edentulous or dentulous mandible cases, and also readily usable with interdental types of splints without conflict. It will be further manifest that the feature of variously positioned fastening members to apply retrusive, vertical or protrusive stress as well as auxiliary stabilizing stress is not limited to a two-piece splint but may also be advantageously used in certain one-piece splints.

While the splint comprising the invention has been illustrated and described as having a certain shape and configuration, and the fastening means have been described as mounted in certain portions of the splint sections, it will be understood that variations may be made in the construction of the splint sections and in the character and arrangement of the fastening members without departing from the spirit or scope of the invention.

What I claim is:

1. An external mandibular splint, comprising: left and right sections of complemental shape generally contoured to fit the lower jaw, each of said sections including a chin-engaging portion at the forward end thereof and a temple portion at the rear end thereof; means operatively connecting said splint sections together; and a series of spaced fastening members carried by each of said temple portions, said fastening members being arranged to cooperate with suitable strap or band means for securing the splint sections in place, one of said fastening members being positioned in said temple portion for application of retrusive stress, another for vertical stress, and another for protrusive stress.

2. An external mandibular splint, comprising: left and right sections of complemental shape generally contoured to fit the lower jaw, each of

said sections including a chin-engaging portion at the forward end thereof and a temple portion at the rear end thereof; flexible means connecting said chin-engaging portions together; three horizontally spaced temple loop members carried by each of said temple portions; and attaching means adapted to be connected with corresponding loop members on said splint sections for securing the splint sections in place, one of said temple loops being positioned and cooperable with said attaching means for application of retrusive stress, another for vertical stress, and another for protrusive stress.

3. An external mandibular splint, comprising: left and right transparent plastic sections of complemental shape generally contoured to fit the lower jaw, each of said sections including a chin-engaging portion at the forward end thereof and a temple portion at the rear end thereof; and a metallic loop member embedded in each of said chin-engaging portions, said loop members being arranged to be flexibly connected together with said chin-engaging portions spaced apart a distance depending upon the width of the chin.

4. An external mandibular splint, comprising: left and right sections of complemental shape generally contoured to fit the lower jaw, each of such sections including a chin-engaging portion at the forward end thereof and a temple portion at the rear end thereof, each of said sections having a lower inwardly curved portion extending rearwardly from said chin-engaging portion toward said temple portion and adapted to engage the underside of the jaw; a loop member carried by each of said chin-engaging portions, said loop members being arranged to be flexibly interconnected with said chin-engaging portions spaced apart a distance depending upon the width of the chin; and a loop member carried by each of said inwardly curved portions at a point intermediate the ends of said sections, said last-mentioned loops being adapted to be flexibly interconnected with said sections angularly disposed in accordance with the width of the lower jaw in the distal area.

5. An external mandibular splint, comprising: left and right sections of complemental shape generally contoured to fit the lower jaw, each of such sections including a chin-engaging portion at the forward end thereof and a temple portion at the rear end thereof, each of said sections having a lower inwardly curved portion extending rearwardly from said chin-engaging portion toward said temple portion and adapted to engage the underside of the jaw; a loop member carried by each of said chin-engaging portions, said loop members being arranged to be flexibly interconnected with said chin-engaging portions spaced apart a distance depending upon the width of the chin; a loop member carried by each of said inwardly curved portions at a point intermediate the ends of said sections, said last-mentioned loop members being adapted to be flexibly interconnected with said sections angularly disposed in accordance with the width of the lower jaw in the distal area; and at least one loop member carried by each of said temple portions arranged to cooperate with suitable headgear means for securing the splint sections in place.

6. An external mandibular splint, comprising: left and right sections of complemental shape generally contoured to fit the lower jaw, each of

said sections including a chin-engaging portion at the forward end thereof and a temple portion at the rear end thereof, each of said sections also having a lower inwardly curved portion extending rearwardly from said chin-engaging portion toward said temple portion and adapted to engage the under side of the jaw; flexible means in front of said chin-engaging portions interconnecting said chin-engaging portions, with said chin-engaging portions spaced apart a distance depending upon the width of the chin; flexible means below said inwardly curved portions interconnecting said inwardly curved portions at a point intermediate the ends of said sections with said sections angularly arranged in accordance with the width of the lower jaw in the distal area; and head gear means interconnecting said temple portions arranged to serve as an attaching means for securing the splint sections in place.

7. An external mandibular splint, comprising: left and right sections of complementary shape generally contoured to fit the lower jaw, each of said sections including a chin-engaging portion at the forward end thereof and a temple portion at the rear end thereof, each of said sections also having a lower inwardly curved portion extending rearwardly from said chin-engaging portion toward said temple portion and adapted to engage the under side of the jaw; a fastening member carried by each of said chin-engaging portions arranged to be interconnected with said chin-engaging portions spaced apart a distance depending upon the width of the chin; a fastening member carried by each of said inwardly curved portions at a point intermediate the ends of said sections and being arranged to be interconnected to angularly space said sections in accordance with the width of the lower jaw in the distal area; and at least one fastening member carried by each of said temple portions arranged to cooperate with suitable head gear means for securing the splint sections in place.

8. An external mandibular splint, comprising: left and right sections of complementary shape generally contoured to fit the lower jaw, each of said sections including a chin-engaging portion at the forward end thereof and a temple portion at the rear end thereof, each of said sections also having a lower inwardly curved portion extending rearwardly from said chin-engaging portion toward said temple portion and adapted to engage the under side of the jaw; a loop member carried by each of said chin-engaging portions, adjustable means interconnecting said loop members with said chin-engaging portions spaced apart a distance depending upon the width of the chin; a second loop member carried by each of said inwardly curved portions at a point intermediate the ends of said sections; and adjustable means interconnecting said second loop members to angularly space said sections. 50 55 60

9. An external mandibular splint, comprising: left and right sections of complementary shape generally contoured to fit the lower jaw, each of said sections including a chin-engaging portion at the forward end thereof and a temple portion 65

at the rear end thereof, each of said sections also having a lower inwardly curved portion extending rearwardly from said chin-engaging portion toward said temple portion and adapted to engage the under side of the jaw; a loop member carried by each of said chin-engaging portions; adjustable means interconnecting said loop members with said chin-engaging portions spaced apart a distance depending upon the width of the chin, a second loop member carried by each of said inwardly curved portions at a point intermediate the ends of said sections; adjustable means interconnecting said second-mentioned loop members to angularly space said sections in accordance with the width of the lower jaw in the distal area; and a series of laterally spaced temple loop members carried by each of said temple portions, said temple loop members being arranged to cooperate with suitable fastening means for securing the splint sections in place, one of said temple loops being positioned in said temple portion for application of retrusive stress, another for vertical stress, and another for protrusive stress.

10. An external mandibular splint, comprising:
25 left and right sections of complementary shape generally contoured to fit the lower jaw, each of said sections including a chin-engaging portion at the forward end thereof and a temple portion at the rear end thereof, each of said sections also having a lower inwardly curved portion extending rearwardly from said chin-engaging portion toward said temple portion and adapted to engage the under side of the jaw; a loop member carried by each of said chin-engaging portions; adjustable means interconnecting said loop members with said chin-engaging portions spaced apart a distance depending upon the width of the chin; a second loop member carried by each of said inwardly curved portions at a point intermediate the ends of said sections; adjustable means interconnecting said second-mentioned loop members to angularly space said sections in accordance with the width of the lower jaw in the distal area; a series of laterally spaced temple loop members carried by each of said temple portions; and head gear means adapted to be connected with corresponding loop members on said splint sections for securing the splint sections in place, one of said temple loops being positioned for application of retrusive stress, another for vertical stress, and another for protrusive stress.

11. An external mandibular splint, comprising: a plurality of splint members, each of said splint members being generally contoured to fit the lower jaw and including a chin-engaging portion and a temple portion; and a plurality of fastening means carried by said temple portion, said fastening means being arranged to be connected with suitable headgear means for securing said splint member in place, said fastening means being selectively connectible with said headgear means and cooperable with said headgear means for applying either a retrusive stress, a vertical stress, or a protrusive stress.

JACOB CLEM BUTLER
